UNITED STATES PATENT OFFICE.

AUGUSTUS H. HEISEY, OF NEWARK, OHIO, ASSIGNOR TO A. H. HEISEY & CO., INC., OF NEWARK, OHIO.

DESIGN FOR A CANDLESTICK.

SPECIFICATION forming part of Design No. 37,213, dated November 8, 1904.

Application filed October 8, 1904. Serial No. 227,730. Term of patent 7 years

To all whom it may concern:

Be it known that I, AUGUSTUS H. HEISEY, a citizen of the United States, residing at Newark, in the county of Licking, State of Ohio, have invented a new, original, and ornamental Design for a Candlestick, of which the following is a specification, reference being had to the accompanying drawings, forming a part thereof.

10 Figure 1 is a side elevation of a candlestick, showing my new design. Fig. 2 is a top plan

view of the same; and Fig. 3 is a horizontal section on the line 3 3, Fig. 1, looking downwardly.

What I claim is—

15 The ornamental design for a candlestick, as shown.

AUGUSTUS H. HEISEY.
